(57) **CLAIM**

The ornamental design for a folding table as shown and described.

DESCRIPTION

FIG. 1 is a front, left and top perspective view of a first embodiment of a folding table, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left and top perspective view of the folding table in a usable state of FIG. 1.

FIG. 10 is an enlarged view of detail 10 in FIG. 2.

FIG. 11 is an enlarged view of detail 11 in FIG. 4.

FIG. 12 is a front, left and top perspective view of a second embodiment of the folding table.

FIG. 13 is a rear, right and bottom perspective view thereof.

FIG. 14 is a front elevation view thereof.

FIG. 15 is a rear elevation view thereof.

FIG. 16 is a left side elevation view thereof.

FIG. 17 is a right side elevation view thereof.

FIG. 18 is a top plan view thereof.

FIG. 19 is a bottom plan view thereof.

FIG. 20 is a front, left and top perspective view of the folding table in a usable state of FIG. 12.

FIG. 21 is an enlarged view of detail 21 in FIG. 13; and,

FIG. 22 is an enlarged view of detail 22 in FIG. 15.

The dashed broken lines depict portions of the folding table that form no part of the claimed design.

The dot-dash broken lines in FIGS. 2, 4, 10, 11, 13, 15, 21 and 22 depict the boundaries of the enlargements and form no part of the claimed design.

1 Claim, 22 Drawing Sheets
